DESIGN FOR A COMFORTABLE

Peter Joseph, Brooklyn, N. Y.

Application April 26, 1940, Serial No. 91,966

Term of patent 3½ years

To all whom it may concern:

Be it known that I, Peter Joseph, a citizen of the United States of America, residing in New York city, in the Borough of Brooklyn, county of Kings and State of New York, have invented a new, original, and ornamental Design for a Comfortable, of which the following is a specification, reference being had to the accompanying drawing, forming part thereof, wherein the figure is a plan view of a comfortable showing my new design.

I claim:

The ornamental design for a comfortable, substantially as shown.

PETER JOSEPH.
